FIG. 1 is a front elevational view of a rear door trim panel for an automobile in accordance with our new design;

FIG. 2 is a top plan view of the rear door trim panel in accordance with our new design of FIG. 1;

FIG. 3 is a bottom plan view of the rear door trim panel in accordance with our new design of FIGS. 1 to 2;

FIG. 4 is a left side elevational view of the rear door trim panel in accordance with our new design of FIGS. 1 to 3;

FIG. 5 is a right side elevational view of the rear door trim panel in accordance with our new design of FIGS. 1 to 4;

FIG. 6 is a front, left and bottom side perspective view of the rear door trim panel in accordance with our new design of FIGS. 1 to 5;

FIG. 7 is a front, right and top side perspective view of the rear door trim panel in accordance with our new design of FIGS. 1 to 5; and,

FIG. 8 is a cross sectional view of the rear door trim panel in accordance with our new design as seen along section line 8-8' of FIG. 1.

The rear view of the rear door trim panel forms no part of the claimed design.

The cross sectional view of FIG. 8 is provided to clarify the exact contour or configuration of the exterior surface of the rear door trim panel, and no attempt is made to illustrate features of internal construction.
